RIVET

Alexander S. Mullgardt, Los Angeles, Calif., assignor to Cherry Rivet Company, Los Angeles, Calif., a corporation of California

Application November 2, 1942, Serial No. 464,319

9 Claims. (Cl. 85—40)

This invention relates to a type of rivet which is capable of installation in an opening for the rivet in the parts to be riveted, and which is accessible from only one side. Such rivets generally include a body member having a head and shank, the shank being of sleeve form, and carried on a stem. In performing the riveting operation the assembled body member of the rivet and the stem, are inserted in the opening to be riveted, and while the outer head of the rivet is held against the plates, the stem is forcibly pulled outwardly. The inner end of the stem is provided with an upsetting head that swages or heads the inner end of the shank over the edge of the hole. This type of rivet is used largely in construction work necessitating the use of a great number of rivets; and hence it is desirable to provide a construction for the rivet, which will enable the rivets to be put in place and riveted with rapidity. In order to facilitate the insertion of the rivets quickly in the openings to be riveted, it is necessary to provide a sufficient clearance between the shank of the rivet and the edge of the aligning openings.

In riveting two parts such as two plates together, it is necessary, of course, to have the two plates pressed tightly together when the riveting operation occurs. One of the objects of this invention is to provide a simple method for accomplishing this through the agency of the rivet itself, and also for expanding the shank of the rivet so that it completely fills the opening in which the rivet is applied. The invention also includes the novel features of the rivet that is employed for effecting these objects.

A further object of the invention is to provide such a rivet with means to insure an effective mushrooming or expansion of the inner end of the shank so as to provide an efficient shoulder projecting over the edge of the opening at the inner and inaccessible side of the riveted plates.

A further object of the invention is to provide a stem of such a rivet assembly with means that will operate in the first part of the upsetting movement of the stem, to exert a force to hold the plates together, by commencing with an outward or expanding movement at the inner end of the shank; also to give such means a form which will enable it to cooperate with the upsetting head at the inner end of the stem, to produce an efficient upset head at the inner end of the rivet.

Further objects of the invention will appear hereinafter.

The invention consists in the novel method and

novel parts and combination of parts to be described hereinafter, all of which contribute to produce an efficient rivet, and riveting method.

A preferred embodiment of the invention is described in the following specification, while the broad scope of the invention is pointed out in the appended claims.

In the drawing:

Fig. 1 is a vertical section taken through two superposed plates, and illustrating a rivet embodying this invention, set in place ready to be riveted. This view also indicates a riveting tool connected up to the outer end of the stem, preparatory to upsetting the inner end of the shank of the rivet body. This view shows the rivet assembly in side elevation.

Fig. 2 is a view similar to Fig. 1, but omitting the riveting tool. In this view the rivet body is shown in section, while the stem of the rivet assembly is shown generally in elevation, but a portion broken away to illustrate a detail of the construction.

Fig. 3 is a view similar to Fig. 2, but illustrating the second stage of the riveting operation in which means on the stem operates to start the upsetting of the inner end of the shank.

Fig. 4 is a view similar to Fig. 3, but illustrating the riveting operation completed and with the upper end of the stem broken off so as to leave the inner portion of the stem tightly held within the shank. This view illustrates the presence of a more effective holding shoulder at the inner end of the shank, to project over the edge of the riveted opening.

Fig. 5 is a side elevation and partial section illustrating a modified embodiment of the rivet in which a collar on the stem is not formed integrally with the stem, as in the embodiment of the invention illustrated in Figs. 2 to 4. In this view the upper portion of the stem is broken away, and the collar is illustrated in full lines in its normal position. The collar is also indicated in dotted lines in a relatively shifted position which it assumes during the riveting operation.

Referring particularly to Figs. 2 to 4 inclusive, in practicing the invention I employ a rivet assembly including a rivet body having a head 1 and an integral shank 2, which is of sleeve form so that it presents a bore received on a stem 3 that fits in the bore. This stem preferably fits friction-tight in the bore, so that the stem will maintain itself within the rivet body in substantially the relation indicated in Fig. 2. In forming this rivet assembly, the pulling head 4 at the outer end of the stem is upset on the stem

after the rivet body is slid over the outer end of the stem, that is to say, on the end of the stem that is remote from the upsetting head 5. Adjacent the upsetting head 5 the stem is preferably formed with a neck 6 of slightly larger diameter than the relatively small body portion of the stem 3 as viewed in Fig. 2, a slight tapered shoulder 7 being formed at the junction of the two differing diameters. Adjacent the inner end of the shank 2 the stem 3 is provided with a collar 8, which may be made integral with the stem as illustrated in Fig. 2, or which may be a separate piece from the stem, as will be described hereinafter. This collar 8 is preferably of substantially the same diameter as the upsetting head 5, and this diameter is as large as possible, that is to say, the largest diameter that can be quickly passed through the opening 9 in the superposed plates 10, or similar parts that are to be riveted together.

In Fig. 2 considerable clearance is indicated between the shank and the edge of the opening, but in practice, of course, this clearance would be slight, though it should be sufficient to enable the rivets to be set in place quickly for riveting. The outer side of the collar 8, that is to say, the upper face as viewed in Fig. 2, is preferably an inclined face 11. After setting the rivet in place as illustrated in Fig. 2, a riveting device 12 is employed to effect the upsetting of the shank 2 by forcibly pulling the stem 3 outwardly. It presents an inner sleeve 12a to which cam levers 12b are pivotally attached. This sleeve 12a can be attached to the head 4, and when the levers 12b are pressed forcibly downward, their cams pull the sleeve 12a upwardly; at the same time, the cam levers 12b bear against the body of the tool 12 and hold the outer head 1 of the rivet in place and tightly against the upper face of the upper or outer plate 10. The upward pull on the stem 3, of course, immediately brings the collar 8 into contact with the end of the shank 2, and this collar, particularly by reason of its inclined face 11, causes an expansion of the inner end of the shank in some such manner as illustrated in Fig. 3, causing the lower end of the shank to assume a more or less mushroom form, and thereby squeeze plates 10 tightly together. Soon after the rivet shank assumes the shape indicated in Fig. 3, a continued pull on stem 3 will shear the collar 8 from the stem, permitting further upward movement of the stem. This movement will cause the inclined shoulder 7 to ride up through the sheared opening in the collar, and will cause the slightly enlarged neck 6 to move through the collar and up through the bore of the shank. As the enlarged neck 6 moves up into the shank 2 of the sleeve, it causes an expansion of the shank so that it will tightly fill the rivet opening 9. This is illustrated in Fig. 4 which shows the relation of all the parts when the riveting operation is completed. As the outward or upward movement of the stem continues toward the final condition indicated in Fig. 4, the collar 8 will seat itself on the upper face or shoulder 5a of the upsetting head 5. This shoulder will then exert upward pressure upon the collar 8, pulling the same tightly into the expanded and mushroomed end of the sleeve. This will cause a further mushrooming of the end of the shank, and should form a more substantial shoulder 13 projecting under the inner edge of the opening as illustrated in Fig. 4. The inclination of the inclined face 11, of course, assists in forming this shoulder 13 because it will develop an expanding force com-

posed of stresses in the mushroomed head acting along lines normal to the conical face of the collar.

If desired, the collar, such as the collar 8, need not be made integral with the stem; and in Fig. 5 I illustrate a construction in which the collar 14 is formed as a separate piece from the stem 15. This collar would be very tight, however, on the stem—sufficiently tight to insure that when it moves relatively back onto the tapered shoulder 16, it will operate to enter the inner end of the shank and start the upsetting operation much like the operation of the other collar 8, as illustrated in Fig. 3.

In the operation of both of these forms of this invention, the enlarged neck 6, and the enlarged neck 17 of Fig. 5, develop a slight expansion of the collar, as this enlarged diameter passes up through the collar. This develops an effective mushrooming and upsetting of the inner end of the shank.

Although I have illustrated this rivet assembly as having a pulling head 4 to enable it to cooperate with a riveting tool such as illustrated in Fig. 1, it should be understood that other riveting tools are employed for use with this type of rivet, in which two jaws are employed that clamp the side of the stem 3. If the rivet is to be used with such a tool, it will be unnecessary, of course, to form any pulling head such as the pulling head 4 on the stem.

It is also not essential to provide the upsetting head 5 at the inner end of the rivet, if the riveting "gun" employed has a limit stop to prevent pulling the rivet stem too far. The inner head 5, however, does provide a stop for the collar to prevent the stem passing out of the collar.

After the upsetting operation is completed, the outer portion of the stem is cut off or broken off at the shoulder 7 which, in practice, would be then located substantially flush with the outer face of the outer rivet head 1.

Many other embodiments of the invention may be resorted to without departing from the spirit of the invention.

What I claim is:

1. In an upsettable rivet assembly for riveting plates in an opening for the rivet accessible from only one side, the combination of a rivet body having a sleeve-form shank for fitting into the opening, a stem carried in the bore of the sleeve and substantially filling the same, and having an upsetting head at its inner end forming a shoulder, and a collar located on the stem at a point removed from the upsetting head and between the upsetting head and the shank end, for engaging the shank before the upsetting head commences to act, said collar having a conical face with its larger diameter disposed toward the upsetting head, operating to engage the end face of the shank and force the end face of the shank outwardly to start the upsetting movement, and operating to seat substantially against the upsetting head at the termination of the upsetting movement of the stem.

2. In an upsettable rivet assembly for riveting plates together through an opening accessible from only one side, the combination of a rivet body having a sleeve-form shank for fitting into the opening through the plates, and having a bore of substantially uniform diameter, a stem having a body portion of relatively small uniform diameter fitting closely within the bore of the shank and having a neck of relatively larger diameter outside of the shank lying adjacent the

inner end of the shank, and a collar carried on said stem, capable of offering considerable resistance to movement along the stem, said collar having a substantially conical face with its larger diameter located toward the inner end of said stem, and operating when the stem is pulled, to upset the shank and form a shoulder extending over the edge of the said opening while said collar maintains its position on the stem, and so that the tension in the rivet stem exerted at the said shoulder pulls the said plates firmly together; said collar operating thereafter when the force pulling the stem is increased to overcome the resistance of said collar and move the same relatively rearwardly on the stem and onto the said relatively larger neck, said neck then operating to expand the said collar and thereby develop a further upsetting effect at said shoulder; said neck operating to pass into the said shank and expand the same to fill the said opening.

3. In an upsettable rivet assembly for riveting plates in an opening for the rivet, accessible from only one side, the combination of a rivet body having a sleeve-form shank for fitting into the opening, said shank having a bore of substantially uniform diameter, said rivet including a stem having a part of substantially uniform diameter fitting closely into the bore of the shank, said stem having an upsetting head at its inner end, and a collar tight on the stem between the upsetting head and the said shank, operating when the stem is pulled outwardly, to force the extreme end of the shank outwardly beyond the edge of the opening to start the forming of a head on the shank, and thereafter operating to slip back relatively on the stem to rest upon the upsetting head, and cooperating thereafter with the upsetting head to complete the forming of an upset head on the inner end of the tubular shank.

4. An upsettable rivet assembly according to claim 3, in which the stem is provided with a neck of enlarged diameter adjacent the upsetting head, operating first to expand the collar and thereafter to expand the shank to fill the rivet opening in the plates.

5. An upsettable rivet assembly according to claim 3, in which the said collar on the stem is formed integrally with the stem, said collar operating to become sheared from the stem by the pressure of the collar against the end of the shank.

6. A rivet assembly comprising: a rivet body having a tubular bore, a stem slidable in the bore of said rivet body and having an enlarged por-

tion of uniform diameter forming an expander mandrel adapted to be drawn into said rivet body to spread uniformly the rivet body sufficiently to take up the initial clearance between the rivet body and the rivet hole; an upset-initiating flange on said stem adjacent said mandrel, said flange being adapted to slide on said stem and stretch over said mandrel only upon being urged against said rivet body with sufficient force to initiate upset-expansion of said rivet body, and a head on said mandrel limiting movement of said flange and adapted to complete the upsetting of said rivet body.

7. In a blind rivet assembly wherein a pulling stem is drawn through a tubular rivet, to force an expander mandrel into said rivet until limited by an upsetting head adapted to clinch said rivet by upsetting the extended end of said rivet, the combination of an upset-initiating means comprising: a flange fixed on said pulling stem and positioned to engage said rivet, the connection between said flange and stem being capable of yielding after said flange effects an initial upset of said rivet, thereupon said flange slides over said mandrel and against said head.

8. In a blind rivet assembly wherein a pulling stem is drawn through a tubular rivet until limited by an expander mandrel and upsetting head, the latter offering sufficient resistance upon upsetting said rivet that said stem may be pulled in two, the combination of: an upset-initiating flange positioned on said stem to engage said rivet prior to said mandrel and head and effect an initial upset, the connection between said flange and said stem being arranged to yield upon such initial upset of said rivet whereupon said flange is adapted to slide over said mandrel and abut said head.

9. A rivet assembly, comprising: a tubular rivet body having a head at one end, the other end being adapted to be upset; a rivet setting stem including a shank portion slidable in the bore of said rivet body, an expander mandrel adapted to be drawn into said body by said shank portion, and an upsetting head at one end of said mandrel forming therewith a stop shoulder; and an upset-initiating flange on said shank portion, said flange being yieldable when forced against said rivet body sufficiently to effect an initial upset-expansion of said body and thereupon become slidable on said shank portion and mandrel until limited by said stop shoulder.

ALEXANDER S. MULLGARDT.
